Primary Examiner — Daniel J Domino*Assistant Examiner* — Samina Vieth(74) *Attorney, Agent, or Firm* — Innovation Capital Law Group, LLP; Vic Lin(57) **CLAIM**

The ornamental design for an antenna, as shown and described.

DESCRIPTION

FIG. 1 is a bottom plan view of an antenna, showing our new design;

FIG. 2 is a bottom perspective view thereof;

FIG. 3 is a top plan view thereof; and,

FIG. 4 is a top perspective view thereof.

The depth of the antenna, as would be seen in the front, rear, and side views, forms no part of the claim.

1 Claim, 4 Drawing Sheets(56)
